ULTRAVIOLET LAMP

George Sperti, Covington, Ky., assignor to Sperti
Lamp Corporation, New York, N. Y., a corpora-
tion of Delaware

Application February 13, 1932, Serial No. 592,742

4 Claims. (Cl. 176—122)

This invention relates to light sources which emit principally in the ultra-violet portion of the spectrum and more particularly to ultra-violet arc lamps.

- 5 In recent years the use of ultra-violet light for various purposes has greatly increased. For example, ultra-violet light is used to irradiate ergosterol and other foods for the purpose of creating antirachitic properties therein; for the direct 10 irradiation of both human beings and animals as a protection against rickets and for general health purposes; the use of ultra-violet light has been suggested for hatcheries and stables, for the sterilization of foods and other products, etc. In 15 some cases, the use of ultra-violet light requires radiations of predetermined wave lengths such as wave lengths longer than 2900 angstrom units, because shorter wave lengths may produce harmful results in such cases as the activation of foods, 20 irradiation of human beings, plants and animals, etc. In other cases, such as sterilization, the short wave length limit may be different or it may be desired to use all of the ultra-violet light available.
- 25 In view of these increased uses of ultra-violet radiation, there has been an increased demand for suitable sources of ultra-violet light which operate efficiently and economically and do not require too much equipment in addition to the 30 lamp itself. The most suitable source of ultra-violet has thus far been found to be an arc between suitable electrodes in an atmosphere of ionized gas or vapor which may comprise mercury vapor, vapors of other relatively volatile metals, 35 gases such as neon and argon, etc., the nature of the arc atmosphere depending to some extent on the radiations which are to be produced.

The present invention relates to an arc lamp of this type radiating in the ultra-violet region 40 of the spectrum and designed for any of the uses mentioned above wherein the ultra-violet radiation is of value. For such purposes the amount of ultra-violet radiation should be increased as much as possible and the visible radiation is not important.

One of the objects of the present invention is to provide an improved and novel ultra-violet lamp which is structurally simple and inexpensive to manufacture, economical to use, and efficient in the production of the desired ultra-violet 45 radiations.

Another object is to provide a novel arc lamp arranged to prevent the escape of heat from the lamp by conduction and convection so as to permit 50 continued operation at temperatures which

are most efficient for the production of the desired ultra-violet radiation.

Another object is to provide a novel ultra-violet lamp wherein the arc temperature is increased and whereby higher boiling point elements can 5 be employed for the arc.

A further object is to provide a novel ultra-violet lamp wherein separate circuits are employed for heating the arc electrodes and for supplying the arc current whereby the characteristics of these circuits can be determined independently.

Another object is to provide a novel ultra-violet arc lamp which is self-contained and self-starting.

With the above objects in view, the invention in its broader aspects includes suitable means for establishing and maintaining an arc in mercury or other vapor in a suitable bulb or chamber which is insulated to prevent the escape of heat, 20 the bulb transmitting the desired radiations and notwithstanding the temperature developed. In a preferred form, the arc bulb or chamber is suitably mounted and enclosed in an outer bulb or chamber which is highly evacuated, and the arc 25 chamber is mounted so as to reduce as much as possible the possible paths whereby thermal conduction from the lamp can take place. In many cases the heat generated by the arc itself will be sufficient to maintain the arc chamber at the 30 desired temperature, in view of the provision of heat insulation, but if desired, additional heat producing means such as heating coils may also be embodied in the lamp, the effectiveness of such additional heating means being greatly increased 35 by insulating the lamp. The heat insulation, with or without the heating coil, makes it practicable to operate the arc at a higher temperature and hence to increase the amount of ultra-violet energy emitted. The invention also makes it 40 practicable to obtain arc spectra of other elements of higher boiling points such as magnesium, cadmium, caesium, etc.

Two embodiments of the invention have been illustrated in the accompanying drawings, but 45 it is to be expressly understood that said drawings are for purposes of illustration only and are not to be construed as a definition of the limits of the invention, reference being had to the appended claims for this purpose.

In the drawings,

Fig. 1 is a view partly in section of a lamp embodying the invention;

Fig. 2 is a detail view, partly in section, of a portion of the lamp shown in Fig. 1;

15

50

55

Fig. 3 is a perspective view of another form of lamp embodying the invention; and

Fig. 4 is a sectional view of the lamp shown in Fig. 3.

Referring now to Figs. 1 and 2, the lamp bulb 1 is of any suitable type, size and shape and is mounted in any suitable base 2. The material of which the bulb 1 is made transmits ultra-violet light at least of the desired wave lengths. For instance, the bulb 1 may be constructed of quartz glass or of any other known glass which transmits ultra-violet radiations. Where it is desired to filter out the radiations shorter than a predetermined wave length, the bulb 1 may be of material having the desired filtering characteristics, although these characteristics are not essential for reasons pointed out hereinafter. The base 2, in the form shown, is of a type analogous to that employed with radio tubes. Sealed in the neck 20 of the bulb 1 is the usual stem or standard 3, of glass or other suitable material, which constitutes the usual means for introducing the necessary conductors into the lamp and for supporting the various elements within the lamp. The bulb 25 1 is evacuated, preferably to the highest practically possible degree. Mounted in any suitable manner within the bulb 1 is an inner bulb or arc chamber 4 which as shown is supported by a band 5 and supports 6 and 7 that are fused in the standard 3. A stem or standard 8 is sealed in the neck of said inner bulb, and this bulb is also of material which transmits ultra-violet light and withstands the temperatures developed. Where it is desired to filter out radiations shorter than 35 a predetermined wave length the material of the bulb 4 may be opaque to wave lengths shorter than those desired, or filtering media may be employed, either with or without the additional filtering at the outer bulb 1. Pyrex glass is heat resistant and has good transmission for ultra-violet radiation down to about 2900 Angstrom units. Quartz glass transmits ultra-violet radiations freely down to about 2000 Angstrom units or below, while certain special glasses have very low 40 transmission for wave lengths shorter than 2800 to 2900 Angstrom units. The structure thus far described and including the two bulbs and means for sealing and mounting the same is disclosed and claimed in copending applications and illustrates a practical form of lamp in which the invention may be embodied.

While the arc electrodes may have any suitable form, they are preferably of a type which renders the arc self-starting so as to avoid the necessity 55 for tilting or otherwise manipulating the lamp to start the arc. As shown, the arc electrodes are of a type disclosed and claimed in a copending application of George Sperti, Serial No. 588,747, filed January 25, 1932. Referring to Figs. 1 and 2, the electrodes comprise tubes or sleeves 9 and 10 of any suitable material such as nickel, tungsten, zirconium oxide, etc., preferably coated on their non-adjacent ends with one or more oxides having high electronic emission when heated such 60 as thorium oxide, strontium oxide, barium oxide, etc. The sleeves 9 and 10 may be provided at their adjacent ends with caps 11 and 12 respectively which caps are formed of material which constitutes a good arcing surface, these 65 caps being uncoated. Tungsten, zirconium oxide, and the like are suitable materials for the arcing surfaces. The inner bulb also contains a quantity of suitable ionizable material, the nature of which depends on the radiations to be produced.

A suitable lamp circuit is provided which not

only supplies potential to the electrodes 9 and 10 but also includes means for heating the electrodes to start the arc, this heating causing electronic emission from the oxide coatings and ionizing the arc atmosphere. Preferably two sources of current at different potentials are provided for heating the electrodes and for establishing the arc therebetween, and separate lamp circuits and terminals are provided in order that the characteristics of these circuits can be regulated and controlled independently. Preferably also the leads within the arc chamber are protected in order to prevent the arc striking between the high potential leads to the electrodes, with constant danger of burning them out, and to these ends the electrodes are shown supported in a manner described and claimed in a copending application of George Sperti, Serial No. 592,745 issued May 1, 1934, as Patent No. 1,956,599. Within the arc chamber are tubes 13 and 14 of suitable insulating material 20 such as magnesium oxide, these tubes being arranged in spaced parallel relation and being secured together and carrying the electrodes between them by means of metal straps 15 and 16 that are passed around the elements and crimped 25 between the elements. The unitary structure thus formed, including the electrodes 9 and 10 and the tubes 13 and 14, is supported within the arc chamber by means of supporting wires 17 and 18 that are preferably welded to the lower metallic strap 16 and are fused in the stem 8.

For heating the electrodes 9 and 10, current is supplied by conductors 19 and 20 connected respectively to base terminals 21 and 22. The conductor 19 is connected to the supporting wire 17 and a wire 23 leads from the support 7 through the stem 8 and the insulating tube 14 to one end of a heating filament 24 within the electrode 9. A wire 25 connected to the other end of the heating filament 24 passes through the insulating tube 13 and leads to one end of a heating filament 26 within the electrode 10, the other end of the filament 26 being connected to the wire 20. Filaments 24 and 26 are insulated from the electrodes in any suitable manner, as by coating them with a 45 suitable refractory cement.

Arc potential is supplied to the electrodes 9 and 10 by wires 27 and 28 connected respectively to base terminals 29 and 30. The wire 28 passes through the stem 8 and the stem 3 and is connected to the electrode 10 by means of the metal supporting strap 16. The wire 27 may be connected to the electrode 9 in a similar manner but for convenience is shown connected to the wire 25, said wire being connected to the metal supporting strap 15 by means of a wire 31.

Any suitable means may be employed for supplying current to the lamp, either in the form of two separate sources of different potential or as shown by two windings of a transformer. A 60 suitable socket is shown diagrammatically at 32 which socket comprises four terminals. Socket terminals 33 and 34 engage the base terminals 21 and 22 respectively and are connected by wires 35 to a secondary transformer winding 36 associated with a primary transformer winding 37. Socket terminals 38 and 39 engage respectively base terminals 29 and 30 and are connected by wires 40 with a secondary transformer winding 41 associated with the primary winding 37.

When current is supplied to the transformer, the winding 36 is energized and current is supplied to a circuit including one of the wires 35, terminals 33 and 21, wire 19, support 7, wire 23, filament 24, wire 25 filament 26, wire 28, termi- 70

nals 22 and 34, and the other wire 35. The heating filaments 24 and 26 heat the electrodes 9 and 10 and also impart heat to the gas or vapor within the arc chamber which is quickly ionized by the heat and also by the electronic emission from the oxide coatings of the electrodes. At the same time the winding 41 is energized and arc potential is supplied to the electrodes by a circuit comprising one of the wires 40, terminals 39 and 30, wire 28, electrode 10, electrode 9, wire 21, wire 25, wire 27, terminals 28 and 38, and the other wire 40. As soon as the arc atmosphere becomes ionized the arc strikes between the electrodes 9 and 10.

It will be seen that the only thermal paths from the arc chamber to the outside of the lamp are by way of the supporting wires 6 and 7. The evacuated bulb 1 constitutes an effective heat insulating means which surrounds the entire arc chamber but at the same time does not interfere in any way with ultra-violet radiation therefrom. The arc chamber therefore rapidly heats up to a relatively high temperature, due both to the heat from the filaments 24 and 26 and to the heat generated by the arc itself.

In most cases the heat generated in these ways will be sufficient to maintain the arc chamber at the desired operating temperature, but in some instances, particularly where the arc chamber contains relatively high boiling point elements, additional sources of heat may be desirable. Figs. 3 and 4 illustrate a lamp embodying an additional source of heat for the arc chamber comprising a heating coil. For convenience, the lamp illustrated is generally the same as that illustrated in Figs. 1 and 2 except for the addition of a heating coil and hence corresponding elements are indicated by primed numerals. Referring now to these figures, the arc chamber 4' is shaped at one end to provide an annular well 42 which, as shown, may contain a quantity of ionizable material, the end of the arc chamber extending inwardly at 43 for this purpose. In the space thus formed on the outside of the arc chamber is wound a heating coil 44 of suitable material such as nichrome alloy which may be energized in any suitable manner. Preferably and in order to reduce the number of leads from the lamp, the opposite ends of the coil 44 are connected to wires 45 and 46 which are in turn connected across the wires 27' and 28' which supply potential to the electrodes 9' and 10'. The heat from the coil 44 assists in vaporizing and ionizing the arc atmosphere initially and in maintaining a high operating temperature in the arc chamber during arc operation.

The invention thus provides an arc enclosed within a bulb or chamber and surrounded by an evacuated space which effectively prevents the escape of heat from the device. The effect produced is analogous to that obtained in a thermos bottle, and the result is that the arc operates at a higher temperature than would be maintained without the heat insulation. The ultra-violet radiation from an arc such as the mercury arc increases in quantity as the operating temperature is increased. Moreover, when it is desired to use higher boiling point elements for the arc, the required operating temperature may be obtained in the arc chamber, the heating coil being added if necessary. Thus in addition to the usual materials such as mercury vapor and gases such as neon, argon, etc., it is possible to use materials such as magnesium, caesium, cadmium, etc., or

their compounds, and to obtain the characteristic spectra of these materials. Magnesium, for example, is advantageous because it radiates a relatively large proportion of its energy in the region between 2900 and 3100 angstrom units but does not emit strongly at shorter wave lengths and hence is very desirable for many purposes. The lamp is small and compact, substantially self-contained, and self-starting, and the separate circuits employed for heating the electrodes and supplying the arc make it possible to determine the characteristics of these circuits independently.

While only two embodiments of the invention have been described and illustrated in the drawings, it is to be understood that the invention is capable of various physical embodiments and that changes may be made in the form, details of construction and arrangement of the parts without departing from the spirit of the invention. It will also be understood that the invention is not restricted to the particular type of lamp shown, to the particular form of electrodes or to the particular means for supporting the various elements within the lamp, which are here shown merely to illustrate a practical form of lamp in which the invention may be embodied. Reference is therefore to be had to the appended claims for a definition of the limits of the invention.

What is claimed is:

1. An arc lamp comprising an outer bulb, an inner bulb mounted therein and spaced from the walls thereof, arc electrodes in said inner bulb, an annular well formed in the wall of said inner bulb and containing a quantity of ionizable material, a heating coil in the space surrounded by said annular well, terminals for said lamp, and means for connecting said electrodes and coil to said terminals, said outer bulb being evacuated whereby said arc bulb and coil are completely enclosed in an evacuated, heat insulating chamber.

2. An arc lamp comprising an arc bulb, a pair of electrodes and a quantity of ionizable material in said bulb, heating filaments for said electrodes, two pairs of terminals for said lamp, means connecting said filaments across one pair of terminals, means connecting said electrodes to the other pair of terminals, and an outer evacuated bulb in which said inner bulb is enclosed.

3. An arc lamp comprising an arc bulb, a pair of hollow electrodes and a quantity of ionizable material in said bulb, heating filaments within and insulated from said hollow electrodes, two pairs of terminals for said lamp, means connecting said filaments in series across one pair of terminals, means connecting said electrodes to the other pair of terminals, an outer evacuated bulb, and means for supporting said arc bulb within and spaced from the walls of said outer bulb.

4. An arc lamp comprising an arc bulb, a pair of hollow electrodes and a quantity of ionizable material in said bulb, heating filaments within and insulated from said hollow electrodes, a heating coil for said arc bulb, two pairs of terminals for said lamp, means connecting said heating filaments to one pair of terminals, means connecting said electrodes and heating coil to the other pair of terminals, an outer evacuated bulb, and means for mounting said arc bulb within and spaced from the walls of said outer bulb.

GEORGE SPERTI.
